UNITED STATES PATENT OFFICE.

JOHN O. MCKEAN, OF WESTFIELD, MASSACHUSETTS, ASSIGNOR TO FOSTER MACHINE COMPANY, OF WESTFIELD, MASSACHUSETTS, A CORPORATION OF MASSACHUSETTS.

DEVICE FOR GUIDING, CLEARING, AND TENSIONING YARN.

Application filed January 6, 1922. Serial No. 527,838.

To all whom it may concern:

Be it known that I, JOHN O. MCKEAN, a citizen of the United States, and resident of Westfield, in the county of Hampden and 5 State of Massachusetts, have invented a new and useful Improvement in Devices for Guiding, Clearing, and Tensioning Yarn, of which the following is a specification.

The object of my invention is to provide 10 certain improvements in the construction, form and arrangement of the several parts of a device for guiding, clearing and tensioning yarn whereby the gravity operated disc of the tension device can be readily removed 15 when so desired and in which the use of the usual pin carried by the bracket on which the disc is mounted, is obviated.

My invention comprises a bracket provided with a yarn supporting platform on 20 which the gravity operated weighted disc is loosely mounted for lateral and vertical movement, means being provided exterior to the disc for limiting its lateral and upward movements.

25 A practical embodiment of my invention is represented in the accompanying drawings, in which

Fig. 1 represents a top plan view of the device.

30 Fig. 2 represents a side elevation.

Fig. 3 represents a bottom plan.

Fig. 4 represents a front view.

Fig. 5 represents a back view, the guard being shown in full lines in its lowered position and in dotted lines in its raised position.

Fig. 6 represents a section taken in the plane of the line VI—VI of Fig. 1.

The bracket herein shown is preferably a 40 casting comprising a resilient yoke, the lower branch of which is denoted by 1 and the upper branch by 2. These two branches are provided with lateral extensions 3 and 4, forming between them a slit 5 for the passage of the yarn. The lateral extension 3 is provided with an uprising pin 6 extending across the slit 5 to serve as a guide for the yarn as it passes from the device.

The lower branch 1 of the bracket is provided with a horizontally disposed platform 7, forming a support for the yarn as it passes through the tension device, which platform is connected to the lower lateral extension 3 of the branch 1 by the web 8 and also to the 55 lower branch 1 by the web 9 over which web

the yarn passes to the tension device. A V-shaped yarn guide 10 projects from the yarn supporting platform 7. This yarn supporting platform is provided with a hole 11 therethrough for the reception of the depending lug of the tension disc, to be immediately described, said hole having downwardly flaring walls, whereby the waste and seed from the yarn will readily fall through the hole without any tendency to stick to the 60 walls as would be the case if the walls were parallel.

The freely rotatable gravity operated weighted disc 12 is loosely mounted on the yarn supporting platform 7 for limited lateral and vertical movements. The means for limiting the upward movement of the disc being movable out of the way when so desired, for permitting the ready removal of 70 the disc from the device.

This gravity operated weighted disc 12 is shown as provided with aligned depending and uprising lugs 13 and 14 of considerable length, the depending lug 13 projecting through the hole 11 in the yarn supporting 80 platform 7, said hole being sufficiently larger than the lug to permit the limited lateral movement of the disc on the platform. This hole is preferably elongated to permit a greater lateral movement of the disc at right 85 angles to the path of the yarn. The uprising lug 14 of the disc serves as a mounting for additional weights when required, as is usual.

An overhanging guard 15 serves to coact 90 with the top of the uprising lug 14 of the disc to retain the disc in its cooperative relationship with the yarn supporting platform and also to limit the upward movement of the disc away from said platform. 95 This guard 15 is movable out of the way when so desired, to permit the removal of the disc; in the present instance by hinging the guard on the pivot 16 between two ears 17, 18, uprising from the upper branch 2 of 10 the bracket, a pin 19 being provided to act as a stop for limiting the downward movement of the guard, and a spring 20 being provided for yieldingly holding the guard in its raised or lowered positions. The lower 10 branch 1 of the yoke is provided with a lug 21 having a hole 22 therethrough for the reception of a crossbar, (not shown) which hole is preferably slightly inclined for tilting the device in a direction tending to slide 1

the disc 12 to the outward limit of its movement on the yarn supporting platform. A set screw 23 serves to secure the bracket to the crossbar (not shown) in the desired adjustment.

From the above description it will be seen that I have provided a tension device in which the use of a pin for mounting the disc is entirely obviated and in which also, means 10 are provided exterior to the disc for limiting its lateral and upward movements, the means for limiting the upward movement of the disc being movable out of the way for ready removal of the disc when so desired.

It is evident that various changes may be resorted to in the construction, form and arrangement of the several parts without departing from the spirit and scope of my 20 invention; hence I do not wish to limit myself to the particular embodiment herein shown and described, but

What I claim is:—

1. In a tension device, a yarn supporting platform, a gravity operated weighted disc loosely mounted thereon for lateral and vertical movements, and means exterior to the disc for limiting the lateral and upward movements of the disc.
2. In a tension device, a yarn supporting platform, a gravity operated weighted disc loosely mounted thereon for lateral and vertical movements, and means exterior to the disc for limiting the lateral and upward movements of the disc, the means for limiting the upward movement being movable to permit the removal of the disc.
3. In a tension device, a yarn supporting platform, a gravity operated weighted disc loosely mounted thereon for lateral and vertical movements, means exterior to the disc for limiting its lateral movement, and means for limiting its upward movement.
4. In a tension device, a yarn supporting platform, a gravity operated weighted disc loosely mounted thereon for lateral and vertical movements, means exterior to the disc for limiting its lateral movement, and means for limiting its upward movement, said last named means being movable to permit the removal of the disc.
5. In a tension device, a yarn supporting platform, a gravity operated weighted disc loosely mounted thereon for lateral and vertical movements, said yarn supporting platform acting as the means for limiting the lateral movement of the disc, and a guard for limiting the vertical movement of the disc.
6. In a tension device, a yarn supporting platform, a gravity operated weighted disc

loosely mounted thereon for lateral and vertical movements, said yarn supporting platform acting as the means for limiting the lateral movement of the disc, and a guard 65 for limiting the vertical movement of the disc, said guard being movable to permit the removal of the disc.

7. In a tension device, a yarn supporting platform having a hole therethrough, a 70 gravity operated weighted disc loosely mounted on the yarn supporting platform and having a depending lug projecting through the hole for limiting the lateral movement of the disc, and a guard for limiting 75 the vertical movement of the disc.

8. In a tension device, a yarn supporting platform having a hole therethrough, a gravity operated weighted disc loosely mounted on the yarn supporting platform and having 80 a depending lug projecting through the hole for limiting the lateral movement of the disc, and a guard for limiting the vertical movement of the disc, said guard being movable to permit the removal of the disc.

9. In a tension device, a bracket including a yarn supporting platform having a hole therethrough, a gravity operated disc loosely mounted on the yarn supporting platform and having a depending lug projecting 90 through the hole for limiting the lateral movement of the disc, and also having an uprising lug, and an overhanging guard for limiting the upward movement of the disc by engagement with said uprising lug. 95

10. In a tension device, a bracket including a yarn supporting platform having a hole therethrough, a gravity operated disc loosely mounted on the yarn supporting platform and having a depending lug projecting 100 through the hole for limiting the lateral movement of the disc, and also having an uprising lug, and an overhanging guard for limiting the upward movement of the disc by engagement with said uprising lug, said 105 guard being hinged to the bracket whereby the guard may be moved out of the way to permit the removal of the disc.

11. In a tension device, a yarn supporting platform having a hole therethrough, the 110 walls of which are downwardly flaring, a gravity operated weighted disc loosely mounted on the yarn supporting platform and having a depending lug projecting through the hole for limiting the lateral 115 movement of the disc, and means for limiting the vertical movement of the disc.

In testimony that I claim the foregoing as my invention, I have signed my name this 4th day of January, 1922.

JOHN O. McKEAN,
